(57) **CLAIM**

The ornamental design for an angle slot pump accessory for a wet and dry vacuum cleaner, as shown and described.

DESCRIPTION

FIG. 1 is a perspective view of an angle slot pump accessory for a wet and dry vacuum cleaner.

FIG. 2 is a top view of the angle slot pump accessory for a wet and dry vacuum cleaner.

FIG. 3 is a front view of the angle slot pump accessory for a wet and dry vacuum cleaner.

FIG. 4 is a side view of the angle slot pump accessory for a wet and dry vacuum cleaner.

FIG. 5 is an opposite side view from FIG. 4 of the angle slot pump accessory for a wet and dry vacuum cleaner.

FIG. 6 is a back view of the angle slot pump accessory for a wet and dry vacuum cleaner.

FIG. 7 is a bottom view of the angle slot pump accessory for a wet and dry vacuum cleaner; and,

FIG. 8 is a perspective view of an exemplary use and attachment of the angle slot pump accessory to a wet and dry vacuum cleaner.

The broken lines of FIGS. 1-8 are for illustrative purposes only and form no part of the claimed design.
